Des. 214,783
Patented July 29, 1969

214,783

BUSMOBILE

Joseph Kurmann, Northridge, Calif. (12087 N. Lopez
Canyon Road, San Fernando, Calif. 91342)

Filed Aug. 30, 1968, Ser. No. 13,335

Term of patent 14 years

Int. Cl. D12—08, 10

U.S. Cl. D14—3

FIG.1

FIG.2

FIG. 3

FIG. 4

FIG. 6

FIG. 5

FIG. 1 is a perspective view of the front and one side of a busmobile showing my new design;

FIG. 2 is a perspective view of the rear and the opposite side of said busmobile;

FIG. 3 is a side elevational view of said busmobile;

FIG. 4 is a side elevational view of the side of said busmobile opposite that shown in FIG. 3;

FIG. 5 is a front view of said busmobile; and

FIG. 6 is a rear view of said busmobile.

I claim:

The ornamental design for a busmobile, substantially as shown.
